UNITED STATES PATENT OFFICE

JOHN VAN BUREN, OF BROOKLYN, NEW YORK

WRAPPING MACHINE

Application filed June 19, 1925. Serial No. 38,167.

This invention relates to wrapping machines and the machine about to be described as an embodiment of the invention has been designed particularly for wrapping cakes of 5 soap, although, of course, the invention is not limited to this specific use.

One of the objects of this invention is to provide a simple and practical mechanism for feeding the articles to be wrapped into the 10 machine.

Another object of the invention is to provide feeding means for the wrapper so constructed and arranged that the feed of the wrappers will be speeded up, thus increasing 15 the capacity or output of the machine.

Another object of the invention is to provide a wrapper feeding mechanism so constructed and arranged that the wrapper will not wrinkle or crumple when it is placed 20 around the article.

Another object of the invention is to provide means for placing wrappers around the article to be wrapped in such a manner that the wrapper will be properly positioned 25 relative to the article and will not draw or slide around the edge of the article.

Another object of the invention is to provide improved mechanism for feeding the packages through the machine in such a 30 manner that the wrapper will not be displaced and the article, such as a cake of soap, will not be damaged.

Another object of the invention is to provide novel and effective means for placing 35 glue or other adhesive on the ends of the wrapper.

Further objects of the invention will appear from the following specification taken 40 in connection with the drawings, which form a part of this application, and in which

Fig. 1 is an elevational view partly in section showing a machine constructed in accordance with the invention;

Fig. 2 is an end elevation of the structure 45 shown in Fig. 1;

Fig. 3 is an enlarged detail sectional view illustrating the wrapper feeding mechanism, the oscillating pocket and a part of the folding mechanism, this view being taken sub- 50 stantially on line 3—3 of Fig. 2;

Fig. 4 is a sectional elevation taken substantially on line 4—4 of Fig. 3;

Fig. 5 is a sectional elevation taken on line 5—5 of Fig. 1;

Fig. 6 is a sectional elevation taken substantially on line 6—6 of Fig. 1;

Fig. 7 is a sectional elevation taken substantially on line 7—7 of Fig. 6;

Fig. 8 is a sectional elevation taken substantially on line 8—8 of Fig. 6;

Fig. 9 is a sectional elevation taken substantially on line 9—9 of Fig. 3; and

Fig. 10 is a sectional elevation taken substantially on line 10—10 of Fig. 3.

The invention briefly described consists of 55 a wrapping machine comprising wrapper feeding means, means for feeding the articles to be wrapped, such as cakes of soap, means for placing the wrapper around the article, for folding the ends of the wrapper, applying 60 adhesive to portions of the ends, and effecting the sealing of the wrapper.

The wrapper feeding means is so constructed and arranged that the wrapper sheets are fed from the hopper in overlapping 75 relation and the foremost sheet is pulled away from or fed ahead of the next succeeding sheet and also ahead of the drive for the feed rolls, the feed rolls being so constructed as to permit this action to take place. The wrapper and article, such as a cake of soap, are fed into an oscillatable pocket and means is provided for placing longitudinal waves in the wrapper to prevent transverse wrinkles therein. It will be understood, however, that as 80 the wrapper and article are fed into the pocket, the wrapper is flattened out and has no waves, creases or wrinkles therein.

From the pocket the package is fed downwardly into vertical guideways where the ends are tucked and folded and each package is fed by the packages positioned above it. From the folding and tucking mechanism, the package passes to the adhesive applying 85 mechanism where glue or other adhesive is applied to the outwardly extending end portions of the wrapper. From this mechanism, the packages are pushed into a guideway in which the ends having the adhesive thereon are folded over the ends of the package. 90

Further details of the invention will appear from the following description.

Wrapper feeding mechanism

5 In the embodiment of the invention illustrated, two wrapper sheets are placed around each cake of soap, these sheets being disposed in hoppers 20 and 21. The hoppers 20 and 21 are open at the bottom and pins or spikes 10 22 extend upwardly into the open bottom and into the lower sheets positioned in the hoppers. Each hopper has a pair of rollers 23 and 24 having thereon projecting portions 25 formed of some such material as rubber 15 and adapted to engage the lower wrapper sheet and feed the sheet laterally from the hopper in position to be engaged by the feed rolls 26 and 27.

Curved guides 28 and 29 receive the sheets 20 from the feed rolls 26 and 27 and direct the sheets downwardly in position to be engaged by feed rolls 30 and 31.

The rolls just described may be driven in any desired manner and in the form of the 25 invention illustrated, a shaft 35 is driven by a chain 36 from drive shaft 37. The shaft 35 is positioned below the hopper 20 and is geared as illustrated to the rollers 23 and 24 below this hopper and the roller 24 is geared 30 through an idler 38 to the rollers 26 and 27 disposed adjacent the hopper 20.

The shaft 35 is connected by a gear 40 and chain 41 to a gear 42 mounted on the shaft of the roller 24 disposed below the hopper 21.

35 This roller is connected through an idler gear 43 to drive the roller 23 and is connected through an idler gear 44 to drive the feed rolls 26 and 27 disposed adjacent the hopper 21. The feed roll 27 just mentioned is connected 40 through an idler 45 to drive the feed rolls 30 and 31.

From a consideration of the operation of the rollers 23 and 24, it will be evident that after the lower sheet in each hopper has been 45 engaged and fed laterally by the rollers 23 and 24, the second sheet or the sheet immediately above the lower sheet will be engaged and fed and this engagement and feeding will take place before the lower sheet has entirely 50 left the hopper. Thus the two lower sheets will be fed simultaneously in overlapping relation into the guides 28 and 29.

The idler gear 45 is so connected to drive the feed rolls 30 and 31 that the feed rolls 55 can rotate ahead of the drive. This connection is made in the following manner. Gear 45 meshes with a gear 46 and gear 46 in turn meshes with a gear 47. Each of these gears has mounted thereon a pawl 48 and these 60 pawls are spring-pressed by springs 49 into engagement with ratchets 50. The ratchets 50 are mounted on shafts 51 which carry the feed rolls. Thus as the gear 45 rotates the gears 46 and 47, these gears in turn through 65 the pawl and ratchet connections rotate the

feed rolls. It will be evident, however, that the feed rolls can rotate in a direction to permit the material to pass therebetween independently of their drive by the gearing connection described, thus permitting the sheets to pass between the rolls ahead of the feed.

Means has been provided for drawing the wrappers through the rolls 30 and 31 at a rate faster than the rate at which they would be fed by the gearing. This means comprises a pair of feed rolls 55 and 56 mounted vertically below the rolls 30 and 31. The roll 55 is carried by a bar 57 adjustably secured to the lower end of a support 58, and the support 58 is secured at its upper end as shown at 59 to a frame member 60.

The roll 56 is carried by a bar 61 vertically adjustable on a support 62 which is hingedly connected at its upper end as shown at 63 to a frame member 64. In order to hold the feed rolls 55 and 56 in coaxing relation, a bolt 65 is pivoted to the support 62 and is adapted to swing between a pair of lugs 66 formed on the support 58. A thumb nut 70 is threaded on the bolt 65 and a spring 71 is positioned between the thumb nut and a washer 72, the washer being disposed in a position to engage the outer edges of the lugs 66. In this manner, the feed rolls 55 and 56 will be held in coaxing relation and in a position to feed the wrapper sheets downwardly. By providing a vertical adjustment for the rolls, the distance from the rolls to the bottom of the slot 105, hereinafter described, can be regulated to accommodate different sizes of sheets.

The feed rolls 55 and 56 as shown in Fig. 9 are so constructed and arranged as to form longitudinal waves in the sheets as they pass therebetween. This is accomplished by providing a plurality of rings or annular portions 75 and 76 on each roll, the rings 75 having a smaller diameter than the rings 76. As illustrated in Fig. 9, the rings 75 on one of the rolls will be disposed opposite rings 76 on the other roll. In this manner longitudinal waves are formed in the sheet and the purpose of these waves is to strengthen the sheet and prevent transverse wrinkling or crumpling.

Guide wires 78 which are disposed on opposite sides of the sheets extend downwardly from the feed rolls 30 and 31 to the feed rolls 55 and 56.

Below the feed rolls 55 and 56 is mounted a guide 79 having an undulating guideway corresponding to the waves formed in the sheets by the rings 75 and 76 carried by the feed rolls 55 and 56.

The rolls 55 and 56 are driven by a gear 80 which in turn is driven by the chain 36.

Article feeding mechanism

It will be understood that the mechanism hereinafter described may be used for feed-

ing and wrapping any desired form of article but the structure was particularly designed for feeding cakes 90 of soap. The cakes are fed by a belt or in any other suitable manner to an inclined chute 92 and from this chute they are pushed onto the top of a reciprocable feeding member or plunger 93 which is driven by a connecting rod 94.

During the forward or feeding movement of this plunger (toward the left in Fig. 1) the foremost cake is moved along until it engages the rear edge of a presser foot 97 which forms a stop and arrests the movement of the cake. As the plunger 93 is retracted, the cakes are prevented from being also retracted by the downward pressure of the cakes on the inclined guide or chute 92. Thus the plunger 93 slides from beneath the foremost cake and permits it to drop on a shelf 95.

In order to insure the proper positioning of the cake on the shelf 95 as shown at 90A in Fig. 1, the presser foot 97 carried by an arm 98 is disposed above the foremost cake and is adapted to engage this cake in position on the shelf 95. The arm 98 is pivoted at 99 and carries a roller 100 engageable by a cam 101 whereby the arm will be tilted and the presser foot will be brought into action at the proper time in the sequence of operations. The cam 101 is carried by a shaft 102 which has mounted thereon a gear or sprocket 103 driven by the chain 36.

When the cake is positioned on the shelf 95, it is disposed directly in front of the forward end of the plunger 93.

Wrapping mechanism

During the operation of feeding the cakes to the shelf 95, the inner and outer wrappers will have been fed downwardly from the chutes 20 and 21 and these operations are so timed that when the plunger 93 moves toward the left in Fig. 1, the wrapper sheets will extend downwardly into a slot 105 across the path of movement of the cake when the cake is fed.

The first element of the wrapping mechanism consists of an oscillating pocket 110 adapted to oscillate from the substantially horizontal position as shown in Fig. 3 in which position it receives the soap and wrappers to vertical position as shown in Fig. 1 from which position the package or the soap and wrappers are discharged into the tucking and folding mechanism hereinafter described.

The oscillating pocket is mounted on a pivot shaft 111 and is substantially U-shaped in section. It will be noted that the pivot shaft is located in a position in alinement with a portion of the pocket. (See Fig. 3.) Thus the cake of soap or other article in the pocket is oscillated through an angle of 90° about an axis intersecting or in alinement with a portion of the article itself. This

minimizes any tendency of the article to be thrown from the pocket during its oscillation. The sides of the pocket carry plates 112 and 113 which are resiliently forced inwardly by springs 114. The plates are mounted on pins 115 which extend through the sides of the pocket and have secured in their outer ends pins 116 which limit the inward movement of the plates under the action of the springs. At each end of the pocket there is secured a lip 118 and as shown in Fig. 5, these lips form tucks 119 in the wrapper at one edge of the ends of the cake.

A plate 120 is disposed in the pocket between the plates 112 and 113 and has secured thereto rods or plungers 121 which extend through the rear wall 122 of the pocket and are slidably therein. The plates 112 and 113 are resiliently pressed against the plate 120.

When the pocket is in the position shown in Fig. 3 but before the cake has been fed thereto, the plate 120 is disposed at the entrance to the pocket. As the cake is fed into the pocket, the rear edge of the cake and the wrapper at that edge engages the plate and this engagement is continued as the cake and wrapper or wrappers are fed into the pocket. By reason of this engagement of the wrapper at the rear edge of the cake with the plate, the wrapper is prevented from sliding around the edge of the cake and thus being displaced. This is an important function of the plate since difficulty has been encountered due to such displacement of the wrappers during the progress of the package through the machine.

When the cake and wrapper are pushed into the pocket by the plunger, the wrapper is positioned around one side or face of the cake, around the rear edge and around the other face of the cake and the remaining portion of the wrapper shown at 125 in Fig. 3 remains in the slot 105. Furthermore, as above explained, the tucks 119 are formed in the ends of the wrapper.

When the cake and wrapper have been placed in the pocket as above described, the pocket 110 is oscillated from the position shown in Fig. 3 to the position shown in Fig. 1 and the portions 125 of the wrappers will be guided by a curved guide surface 126, this guiding function being clearly shown in Fig. 1.

After the oscillating pocket has been moved to vertical position by means of a reciprocating pitman 130, the pocket is disposed in position to have the package discharged therefrom. The pitman 130 is operatively connected to the oscillatory shaft 111 of the pocket by means of a rack 131 formed on the lower bifurcated end of the pitman and a pinion 132 carried by the shaft 111. The pitman is actuated by a cam 133 in which is positioned a roller 134 carried by the pitman.

The rear end of the pitman is bifurcated as shown at 135 and straddles the shaft 37.

The discharge is accomplished by forcing the plungers 121 and the plate 120 downwardly into the pocket, thus forcing the package out of the pocket. The plungers 121 are moved downwardly by an actuating arm 136 having at one end thereof a cross plate 137 adapted to engage the upper end of the plungers 121. The arm 136 is oscillated about a pivot 138 by means of a crank pin 139 carried by the shaft 37 and engaging the slot 140 in the arm 136.

From the pocket 110, the packages are discharged vertically into a vertical guideway 150. At the upper end of the guideway are disposed upwardly extending spring lips 151, these members being disposed on the side edges of the guideway, and being adapted to form tucks 152 in the ends of the wrappers opposite the tucks 119. Thus when the cake reaches the position shown at 90B in Fig. 5, there are two tucks at each end of the wrapper and the wrapper extends outwardly beyond each end of the cake forming substantially parallel projections in alignment with the faces of the cake.

One of these projections at each end of the cake is folded across the end of the cake by means of an inclined slot 153 formed at the side edges of the guideway 150. One projection at each end extends into this slot 153 and is folded by the slot across the end of the cake so that after the cake has passed through the intermediate position in the vertical guideway to the lower position or to a position at the bottom of the guideway, the wrapper will project beyond the ends of the cake only at one edge thereof.

Attention is called to the fact that no extraneous feeding mechanism is provided for engaging the cakes and feeding them downwardly through the guideway, each cake being fed downwardly by the cakes positioned above it. Thus the feeding of the cakes involves no engagement of feeding fingers or other devices with the wrappers, which engagement tends to displace the wrappers, or unwrap the cakes or in some cases to damage the cakes.

The bottom cake shown at 90C in Fig. 7 is positioned above a shelf 160 and is limited in its downward movement by the shelf.

Adhesive applying mechanism

A tray 161 is mounted below the bottom of the vertical guideway and below the cake 90C, this tray being adapted to contain glue or other suitable adhesive. A pair of rollers 162 have their lower portions extending into the glue and engage a pair of disks 163, the rollers 162 being adapted to transfer the adhesive to the disks 163 which in turn transfer the adhesive to the projecting ends 164 of the wrapper (see Fig. 5). The disks

163 are mounted on spindles 165 which are in turn rotatably mounted in the upper ends of arms 166 rotatably mounted on a shaft 167 on which are mounted the rollers 162. Each arm 166 is extended beyond the shaft 167 as shown at 168 and the portion 168 of the arm is engageable by a roller 169 carried by an arm 170 mounted on a shaft 171 which in turn is mounted in brackets 172 secured to the base 173 of the machine. The shaft 171 is oscillated by a crank 174 which is connected by a link 175 to a crank 176 on the shaft 37.

Each of the arms 166 has pivoted thereon a pawl 180 which engages a ratchet 181 connected to the shaft 167.

The shafts 165 and 167 are operatively connected at both ends by gears 182 and 183.

Each ratchet wheel 181 is engaged by a pawl 185 mounted below the ratchet wheel and spring-pressed into engagement therewith by a spring 186. The pawls 185 are mounted on fixed pivots and do not rotate with the ratchet wheels as in the case of pawls 180 carried by the arms 166.

The arms 166 are normally retained in retracted position by means of springs 188 secured to the arms and fixed at their opposite ends as shown at 189.

The adhesive applying mechanism operates in the following manner: When the foremost cake is positioned on the shelf 160, the disks 163 will be retracted and after the cake has been so positioned, the actuating arms 170 will engage the extensions 168 of the links 164 and swing the links in an anti-clockwise direction about the shaft 167. As the links are thus swung, the pawls 180 carried by the links will engage the ratchet wheels 181 and rotate the shaft 167 and the rollers 162. Also by reason of the geared connection 182, 183 between the shafts 165 and 167, the disks 163 will be rotated. In this manner, a supply of adhesive is always insured for the projecting ends 164 of the wrapper.

Package discharging mechanism

After the projecting ends 164 of the wrapper have been supplied with adhesive, the cakes are discharged into a substantially horizontal guideway having a bottom or supporting surface 190 and side walls 191 (see Figs. 2 and 6). The side walls are extended laterally to form flanges 193 and as shown in Fig. 6, the projecting portions 164 of the wrapper are positioned against these flanges when the disks 163 are applying adhesive thereto.

In order to discharge the cakes into the guideway, a reciprocable plunger is mounted in alignment with the guideway and is provided with a plate 201 adapted to engage the packages and force them into the guideway. The plunger has rearwardly extending guide rods 203 slidably mounted in bearings 204.

and the plunger is reciprocated by a pitman or connecting rod 205 pivoted at 206 to the plunger plate 201 and connected at its rear end to a crank 207 mounted on a shaft 208. The shaft 208 has mounted therein a gear or sprocket 209 which is driven by the chain 36.

As the packages are forced by the plunger into the horizontal guideway, the projecting ends 164 are folded across the ends of the cake and are held thereagainst by side walls 191 of the guideway. From the guideway the packages pass between a pair of conveyer belts 210 (one of which is shown) and the cakes are conveyed away from the machine by said conveyers.

Operation

The machine above described operates as follows: Wrapper sheets are fed laterally and downwardly from the hoppers 20 and 21, the feed being accelerated when the sheets are engaged by the feed rollers 55 and 56. This acceleration of the feed is permitted by the rollers 30 and 31 because of the pawl and ratchet drive for these rollers. Longitudinal waves are formed in the sheets as they pass between the rings 75 and 76 carried by the rollers 55 and 56, these waves being formed for the purpose of preventing transverse wrinkles or folds in the sheets.

In the meantime, the cakes 90 have been fed downwardly onto the plunger 93 and one of the cakes will have been positioned on the shelf 95 when the wrapper sheets are disposed in the path of movement of the cake. When these operations have taken place, the pocket 110 will be disposed in receiving position and the foremost cake and wrappers will be forced into the pocket. During the movement of the cake and wrapper into the pocket, the wrapper or wrappers will be prevented from sliding around the cake by reason of the engagement of the sheets with the plate 120. During this movement also tucks 119 will be formed in the ends of the wrapper.

After the wrappers and cake have been placed in the pocket, the pocket will be oscillated to the position shown in Fig. 1 and the plunger rods 121 will be actuated to force the plate 120 to discharge the package into the vertical guideway 150. As the cake and wrappers pass through the guideway, tucks 152 will be formed therein and the wrapper will be folded across the ends of the cake so that portions 164 extend beyond the ends substantially in alinement with one face thereof. The packages are fed downwardly through the guideway by the new packages entering the guideway and when the foremost package is positioned on the shelf 160, adhesive is applied to the projecting ends 164 of the wrapper thereof by means of the disks 163. After the adhesive has been applied, the plunger operates to discharge the cake into the horizontal guideway or passageway.

From the foregoing description it will be clear that a simple and practical machine has been provided for the wrapping and sealing of packages and that the structure described will effectively perform the functions and objects set forth.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a wrapping machine, an oscillatable pocket, means for feeding an article and wrapper into said pocket, means for oscillating the pocket through an angle of substantially 90° from receiving to discharging position and reversely through an angle of substantially 90° to receiving position, a plunger mounted on the pocket for discharging the article and wrapper therefrom and means engageable with said plunger when the pocket has been rotated through 90° to discharging position for actuating the plunger to discharge the article and wrapper from the pocket.

2. In a wrapping machine, an oscillatable pocket, means for feeding an article and wrapper into said pocket, means for oscillating the pocket through an angle of substantially 90° from receiving to discharging position and reversely through an angle of substantially 90° to receiving position, a plate positioned in said pocket and adapted to engage the wrapper and act against the inner edge of the article and means operable on the plate after the pocket has been oscillated through 90° to discharging position to move the plate outwardly in the pocket and discharge the article and wrapper therefrom.

3. In a wrapping machine, an oscillatable pocket pivoted on an axis intersecting the pocket, means for oscillating the pocket through an angle of substantially 90° from a substantially horizontal receiving position to a substantially vertical discharge position, a plate in said pocket, movable from the inner to the outer end thereof, plungers engaging said plate and means engageable with the plungers when the pocket is in discharging position only for actuating said plungers and plate to discharge the article and wrapper from the pocket.

4. In a wrapping machine, an oscillatable pocket movable from receiving position to a substantially vertical position in which the pocket opens downwardly, a vertical guideway having means for folding the wrapper and tucking the ends thereof, means for oscillating the pocket through an angle of substantially 90° from receiving to discharging

- position and reversely through an angle of substantially 90° to receiving position, means for discharging successive packages into said guideway one above the other and so constructed and arranged that each discharge of a package from the pocket will cause the preceding packages to be fed downwardly in the guideway, and means movable in a direction substantially at right angles to the path of movement of the articles through said guideway for discharging the lower package from the guideway.
5. In a wrapping machine, an oscillatable pocket pivoted on an axis intersecting the pocket, means for feeding an article and wrapper into said pocket, means positioned at the open or receiving end of the pocket when the article and wrapper are fed thereto, said means being movable into the pocket by the article and wrapper and being adapted to hold the wrapper from sliding around the edge of the article, means for oscillating the pocket from receiving to discharging position and means for actuating the 25 plate to discharge the article and wrapper from the pocket.

In witness whereof, I have hereunto set my hand this 17th day of June, 1925.

JOHN VAN BUREN.
